ABSTRACT OF THE DISCLOSURE

A closed container having an air inlet and a gyroscope mounted within the container. The inner gimbal of the gyroscope carries a dome-shaped member having a central nozzle opening therethrough. A porous open cellular element is carried by the container and has a surface conforming to and in slightly spaced registry from the dome-shaped member. Air collection chambers are equally spaced about the porous member and have air pickoff passages. An air leak gland is provided about the porous element. Air flowing into the container flows through the nozzle into the porous element where it is transmitted to the collection chambers in proportion to the angular position of the nozzle relative to predetermined axis of the porous element.

The present invention relates to an attitude sensor and particularly to a gyroscope having a pneumatic pickoff wherein deviations in attitude from a predetermined attitude are sensed and translated to pneumatic signals.

Directional control systems in the past have provided complex apparatus for guiding movable bodies along predetermined courses. These apparatus suffer various disadvantages such as relatively high bulk and weight, and space limitations, as well as those factors previously mentioned, are critical in the provision of an attitude sensor.

The present invention provides a gyroscopic directional control system having pneumatic pickoff signals for sensing the attitude deviation of a body from a predetermined attitude and which invention minimizes the above-discussed and other shortcomings of prior directional control systems employed for like purposes and provides various advantages in construction, mode of operation and result over such prior systems. To accomplish this, the present directional control system provides a gyroscope carried within a closed fluid tight container. The container has an air inlet connected with an air supply under pressure and a porous open-cellular element forming a portion of the wall of the container. The inner gimbal of the gyroscope carries a dome-shaped element having a central passage therethrough forming a nozzle. The inner surface of the porous element is concavely spherical to conform with the dome-shaped element. The gyroscope and porous element are located such that the nozzle containing the dome-shaped element lies in slightly spaced registry from the conforming spherical surface of the porous element such that the air flowing into the container flows through the nozzle into the porous element. Air collection chambers are arranged at predetermined spaced positions about the porous element whereby the air issuing through the nozzle and into the porous element is transmitted into the collection chambers for ultimate communication with pneumatic amplifiers connected to an attitude control. Thus, the chambers collect the fluid transmitted through the porous element in proportion to the angular position of the nozzle relative to the element and hence in proportion to the change

2

in attitude of the body mounting the container relative to the gyroscope.

It is a further feature of the present invention that spurious air flow between the dome-shaped member and the porous element is eliminated. To this end, an air leak gland is provided about the porous element such that air in the container flows through the air leak gland without entering the area between the porous element and dome-shaped member in the area of the nozzle. The air issuing through the nozzle thus constitutes the sole air input to the porous element and spurious pneumatic signals are eliminated.

Accordingly, it is a primary object of the present invention to provide an improved directional control device.

It is another object of the present invention to provide a directional control system including a gyroscope with a pneumatic pickoff.

It is still another object of the present invention to provide a directional control system including a gyroscope with a pneumatic pickoff.

It is still another object of the present invention to provide a directional control including a gyroscope with a porous element whereby attitude deviations from a predetermined attitude are sensed by pneumatic signals transmitted through the porous element.

It is a further object of the present invention to provide an attitude control device which is economical to manufacture, simple and efficient in operation, and has excellent sensitivity characteristics.

These and further objects and advantages of the present invention will become more apparent upon reference to the following specification, claims and appended drawings, wherein:

FIGURE 1 is a cross-sectional view of an attitude sensor constructed in accordance with the present invention;

FIGURE 2 is a horizontal cross-sectional view thereof taken about on line 2—2 of FIGURE 1; and

FIGURE 3 is a horizontal cross-sectional view thereof taken about on line 3—3 of FIGURE 1.

Referring now to FIGURE 1, there is shown an attitude sensor generally indicated at 10 comprising a cylindrical, fluid-tight container 12 having circular upper and lower end walls 14 and 16, respectively, and mounting a gyroscope generally indicated at 18. Container 12 has an air inlet conduit 20 which connects to a suitable pneumatic source, not shown, and a circular aperture 22 through upper wall 14 for purposes as will presently become clear.

Gyroscope 18 comprises an outer gimbal 24 pivotally mounted to container 12 in any suitable manner as at 26 and an inner gimbal 28 pivotally mounted to outer gimbal 24 as at 30 such that the pivotal axes of the gimbals lie at right angles to one another. Inner gimbal 28 carries a pair of spaced cross support members 32 which pivotally mount a rotor or rotating mass 34 as at 36. Suitable means, not shown, are provided for rotating rotor 34. It is thus seen that gyro 18 is a free gyro, that is, gyro 18 is not constrained to follow the motions of container 12. It will be understood that the present invention may also be employed with a single axis gyro and that the free gyro disclosed is for illustrative purposes only as the present invention is not limited thereto.

A spherical or dome-shaped member 38 is carried on inner gimbal 28 by means of four upstanding posts 40 which are suitably connected at their lower ends to the upper support 32 of gimbal 28 and connected at their upper ends to the concave underside of member 38. The wall portions 42 about opening 22 conform in shape to the outer convex surface of spherical member 38. Member 38 is slightly spaced from conforming wall portions 42 to provide an annular air leak passage 43 for con-

tinuously transmitting air out of container 12 for purposes as will presently become clear. A central aperture or nozzle 44 is formed through member 38 and this, together with the annular air leak passage 43, form the sole fluid outlets from container 12.

An inverted, cup-shaped container 46 is suitably secured to container 12 in sealing relation about opening 22. Container 46 suitably supports a cylindrical porous element 48 from its upper end. Porous element 48 is preferably formed of a homogenous open cellular material such as an open celled plastic foam or a porous sintered metal. The lower surface 50 of element 48 conforms in shape to the outer surface of member 38, i.e., surface 50 is concavely spherical. Cylindrical element 48 is inwardly spaced from the sidewalls of container 46 as to provide an annular area 52 thereabout. Four fluid outlets 54 are equally spaced about container 46 in fluid communication with annular area 52. Annular area 52 is preferably divided into four quadrants by baffles 56, as shown in FIGURE 3, whereby the annular portions between the baffles comprise quadrantal collection chambers 57 communicating with associated fluid outlets 54. The lower spherically concave surface 50 of element 48 is slightly spaced from the outer convex surface of member 38.

In use, air flows continuously into container 12 via inlet conduit 20 and flows out of container 12 into the quadrantal collection chambers 57 and associated outlets 54 by way of the annular air leak passage 43 or the nozzle 44. It will be appreciated that the air flowing into the quadrantal collection chambers via the air leak passage 43 provides equal air flow into the fluid outlets 54 as the annular passage 43 is symmetrical about the collection quadrants. When the gyro axis, coincident with rotor axis 36, is coincident with the central vertical axis of element 48, it will be seen that air flowing through nozzle 44 will be equally dispersed throughout porous element 48 such that lateral air flow from element 48 into the quadrantal collection chambers provides equal air flow through the outlet conduits 54. Should the container 12 be inclined relative to gyro 18, it will be seen that the nozzle 44 will be offset from the vertical axis of element 48. When this occurs, the air flowing through nozzle 44 will be dispersed throughout porous element 48 with a larger proportion of the air flowing into one or more of the quadrantal collection chambers 57 which lie closer to nozzle 44. Thus, the air flow out of the associated fluid outlets 54 will be greater than the air flow through the other conduits 54 communicating with the collection chambers further spaced from nozzle 44. This change in attitude of the container 12 relative to the gyro is thus sensed and the increased air flow through the one or more outlet conduits 54 can be fed through pneumatic amplifiers, not shown, to provide the desired corrective or stabilizing action of the body, not shown, housing the gyro to which container 12 would be rigidly attached.

It is a significant feature hereof that spurious air flow between the spherical member 38 and the lower surface 50 of porous element 48 which might provide an erroneous pneumatic signal if transmitted through element 48, is entirely eliminated. By providing the annular air leak passage 43 between member 38 and the wall portions 42 of container 12, whereby the continuously flowing air is evenly distributed into the quadrantal collection cham-

bers, air flow between element 48 and member 38 in the area of surface 50 and nozzle 44, other than that air issuing from nozzle 44, is eliminated. Thus, the air issuing through nozzle 44 constitutes the sole air input to porous element 48.

The invention may be embodied in other specific forms without departing from the spirit or essential characteristics thereof. The present embodiment is therefore to be considered in all respects as illustrative and not restrictive.

What is claimed and desired to be secured by United States Letters Patent is:

1. An attitude sensing device comprising a support, a gyroscope having at least one gimbal mounting a rotor and carried by said support, a nozzle carried by said gimbal for discharging fluid under pressure, a fluid transmitting element carried by said support in registry opposite said nozzle for receiving the pressure fluid issuing therefrom, said element being formed of a porous material and having a surface area against which the pressure fluid from said nozzle is directed larger than the exit area of said nozzle, fluid collection passages located at predetermined positions about and in communication with said porous element and adapted to receive fluid transmitted through said element in proportion to the angular position of the nozzle relative to the support.

2. A sensing device according to claim 1 including a dome-shaped member carried by said gimbal, said nozzle comprising a passage through said member, a surface area of said element being concavely spherical and conforming to and in slightly spaced registry with the convex face of the dome-shaped member.

3. A sensing device according to claim 2 wherein said support structure comprises a closed container, said container having a fluid pressure inlet, said element comprising a fluid outlet from said container, the pressure fluid in said container issuing through the passage in said dome-shaped member and through said element into said collection passages.

4. A sensing device according to claim 3 wherein said element is carried by a wall of said container, an air leak opening about said element through said wall and in slightly spaced relation about said member, the pressure fluid in the container flowing through said opening into said collection passages.

5. A sensing device according to claim 1 wherein said passages include fluid collection chambers equally spaced about said element.

6. A sensing device according to claim 1 wherein said element is formed of a sintered metal.

7. A sensing device according to claim 1 wherein said element is formed of an open cellular plastic material.
